(57) **CLAIM**

The ornamental design for a baby bottle as shown and described.

DESCRIPTION

FIG. 1 is a top perspective view of a baby bottle embodying my new design, according to one embodiment;

FIG. 2 is a bottom perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and

FIG. 8 is a bottom view thereof.

FIG. 9 is an exploded view thereof; and

FIG. 10 is a left side view thereof with a cap attached to the baby bottle.

FIG. 11 is a top perspective view of a baby bottle embodying my new design, according to a second embodiment;

FIG. 12 is a bottom perspective view thereof;

FIG. 13 is a left side view thereof;

FIG. 14 is a right side view thereof;

FIG. 15 is a front view thereof;

FIG. 16 is a rear view thereof;

FIG. 17 is a top view thereof; and

FIG. 18 is a bottom view thereof.

FIG. 19 is an exploded view thereof; and

FIG. 20 is a left side view thereof with a cap attached to the baby bottle.

FIG. 21 is a top perspective view of a baby bottle embodying my new design, according to a third embodiment;

FIG. 22 is a bottom perspective view thereof;

(Continued)

FIG. 23 is a top view thereof;
 FIG. 24 is a bottom view thereof;
 FIG. 25 is a left side view thereof;
 FIG. 26 is a right side view thereof;
 FIG. 27 is a front view thereof; and,
 FIG. 28 is a rear view thereof.
 Broken lines are used to illustrate features of the baby bottle
 that form no part of the claimed design.
